(57) **CLAIM**

The ornamental design for a universal bag holder, as shown and described.

DESCRIPTION

FIG. 1 is a front perspective view of a universal bag holder; FIG. 2 is a back perspective view of the universal bag holder;

FIG. 3 is a front view thereof;

FIG. 4 is a back view thereof;

FIG. 5 is a right-side view thereof;

FIG. 6 is a left side view thereof;

FIG. 7 is a top view thereof; and,

FIG. 8 is a bottom view thereof.

The broken line showing of the bags in FIG. 1 depicts environment and forms no part of the claimed design. All other broken lines depict portions of the universal bag holder that form no part of the claimed design.

1 Claim, 8 Drawing Sheets
